VARIABLE CONDENSER

Filed Jan. 21, 1926

UNITED STATES PATENT OFFICE

HARRY H. IDE, OF LA GRANGE, ILLINOIS, ASSIGNOR TO KELLOGG SWITCHBOARD & SUPPLY COMPANY, OF CHICAGO, ILLINOIS, A CORPORATION OF ILLINOIS

VARIABLE CONDENSER

Application filed January 21, 1926. Serial No. 82,638.

This invention relates to improvements in variable condensers and particularly to improvements in condensers having sets of plates which are adjusted relatively to each other in order to vary the capacity of the condenser.

In radio receiving sets and other apparatus it has become common to mount a plurality of variable condensers so as to be simultaneously actuated and adjusted by the same operating means for tuning and other purposes. These condensers may, as shown in the present embodiment of the invention, be mounted on a common shaft or other means may be provided for simultaneously adjusting the several sets of movable plates of the condensers.

Due to slight variations in the material employed, variations in the space between the plates and other incidents of manufacture, the capacities of substantially identical condensers vary slightly; also the characteristics of the apparatus in the circuits with which the several condensers are employed may be such that the circuit function most satisfactorily when the capacity of the several condensers are slightly different.

The objects of the present invention is, therefore, to provide means whereby the initial or basic capacities of the condensers may be adjusted or varied so that each of the condensers of the series or gang of condensers will have the correct capacity to give the most satisfactory results when the several condensers are operated in unison. In the present embodiment of the invention this initial adjustment of the capacity of an individual condenser is accomplished by varying the spacing laterally between certain of the fixed and movable plates of the condenser.

It is believed a further disclosure of the invention will most readily be understood from a detailed description thereof taken in connection with the accompanying drawings in which:

Fig. 1 shows an end view of one of the individual condensers of the present invention;

Fig. 2 is a plan view of the device of Fig. 1;

Fig. 3 is a view of the opposite end of the device shown in Fig. 1;

Fig. 4 is a horizontal view through the condenser along the axis of the shaft;

Fig. 5 is a side view of the condenser looking at the device of Fig. 3 from the right; 55

Fig. 6 is a plan view diagrammatically illustrating a plurality of individual condensers arranged to be operated in unison by single adjusting means. 60

Referring now to the drawings in which like reference characters indicate the same parts in the several views: 10 is the base of the condenser having at the opposite ends thereof the upwardly extending arms 11 and 12, provided at the upper ends thereof with the aligned openings 13 and 14 through which extends the shaft 15. The openings 13 and 14 are counter-sunk on their opposed faces to receive the cone-shaped bearing members 17 and 18 which are fixed to the shaft 15 by means of the set screws 19. 65

Secured to the base 10 on the opposite sides thereof by means of screws 20 are the blocks 21 of insulating material. 70

Secured to each of the blocks 21 by means of rivets 22 is a bracket 23 having upwardly and outwardly extending arms 23' which are connected by means of an integrally formed strip 24 which is provided with notches 25. 80 A plate member 24' provided with notches 25' and which rests on the strip 24 of the bracket 23 cooperates with notches 25 in the strip 24 to form slots 60 adapted to receive the lugs 26 extending outwardly from the opposite lower sides of each of the stationary plates 27. The lugs 26 of the plates 27 may be secured within the notches 25 in any desired manner as by means of solder. Associated 85 with each of the brackets 23 is a terminal clip 27'. Secured to the arm 12 by means of the screw 28 is a bracket 29 provided at the upper end thereof with a split bearing 30 controlled by the set screw 31 by means of which the drag on the shaft may be regulated. 90

The movable plates 32 of the condenser are fixed to the shaft 15 and pass between the fixed plates 27 when the shaft is rotated in the usual manner. These plates may be secured to the shaft 15 in any desired manner. 100

In the present embodiment of the invention each of the plates is provided substantially centrally of its flat side with the upwardly extending portion 33 provided with an opening 5 adapted to receive the shaft 15.

As shown herein there are six movable plates 32 arranged respectively in the spaces between the seven fixed plates 27. Surrounding the shaft on opposite sides of the set of six movable plates are the mounting blocks or plates 34 and 35, (see Fig. 4). Fixed to the block 35 is a sleeve 36 secured to the shaft 15 by means of the set screw 37. The plates or mounting blocks 34 and 35 are rigidly joined by means of the flat plates or strips 38, provided with the slots 39 arranged to receive the edges 40 of notches provided in the upwardly extending portions 33 of the movable plates 32. The plates 32 may be rigidly secured to the strips 38 by solder or in any other desired manner. It will readily be seen that in this structure the group of movable plates is mounted as a rigid unit on the shaft 15, but may be adjusted longitudinally on the shaft in order properly to space the movable plates between the fixed or stationary plates.

As above explained, where the condensers of a receiving or other circuit are arranged to be adjusted simultaneously by a common adjusting means, it is desirable to provide means whereby the initial capacity of the individual condensers of the group may be varied or adjusted. In the present embodiment of the invention this is accomplished by providing an additional or seventh movable plate 41 carried by a collar 42 fixed to the shaft 15 by means of the set screw 43. The plate 41 may be adjusted longitudinally of the shaft 15 to vary the distance between this plate and the outside fixed plate 27 adjacent thereto; thus providing simple means whereby the initial capacities of the condensers may be readily altered.

Referring now to the Fig. 6, a series of three condensers, such as above described, are shown mounted on a common shaft adapted to be rotated by the worm wheel 44 driven by the worm 45 through the medium of the hand wheel 46. The shaft 15 may be one continuous shaft but preferably three of the individual condensers are mounted on a common base or support 47 with their shafts 15 in alignment, the adjacent ends of the shafts being joined by suitable connecting devices 48. Thus when the hand wheel 46 is rotated the movable plates of each of the three condensers are simultaneously operated in a like manner. In order that each of these individual condensers may be adjusted so that the capacities thereof are in accordance with the properties of the section of the receiving circuit with which it is employed the plates 41 may be adjusted longitudinally of the supporting shaft.

While in the above disclosure but a single embodiment of the invention has been dis-

closed it is to be understood that many variations in the details of the invention are contemplated and the invention, therefore, should be limited merely by the scope of the appended claims.

Having described my invention what I claim is new and desire to secure by Letters Patent of the United States is:

1. In a condenser, a plurality of fixed plates, a plurality of movable plates supported on a rotatable shaft, means for moving said movable plates simultaneously in relation to said fixed plates and independent means slidable on said shaft for varying the relation of certain of said movable plates to said fixed plates, said certain movable plates mounted on said rotatable shaft and adapted to be rotated thereby. 70

2. In a condenser, a plurality of fixed plates, a plurality of movable plates associated therewith supported on a rotatable shaft, means for rotatably moving said movable plates simultaneously in relation to said fixed plates and independent means slidable on said shaft for supporting and for varying the space between certain fixed and movable plates, said certain plates adapted to be rotated simultaneously with the other said movable plates. 80

3. In a condenser, a plurality of fixed plates, a plurality of movable plates associated therewith supported on a rotatable shaft, means for rotatably moving said movable plates simultaneously in relation to said fixed plates, means adapted to surround a portion of said shaft and to be adjusted in frictional relation thereto and by means of said frictional engagement to maintain the said movable plates in any adjusted position relative to said fixed plates, and means for adjusting one of said movable plates laterally in relation to the adjacent plates whereby the normal capacity of the condenser may be varied, said laterally adjustable plate supported by said rotatable shaft and adapted to be rotated thereby. 100

4. In a condenser, a plurality of fixed plates, a shaft, a plurality of movable plates carried by said shaft and adapted to be positioned between said fixed plates, respectively, an additional movable plate mounted on a collar adjustably supported on said shaft and means permitting adjustment of said additional plate supported by said collar longitudinally of said shaft independently of said plurality of movable plates. 115

5. In a condenser, a plurality of fixed plates, a shaft, a plurality of movable plates carried by said shaft and adapted to be positioned between said fixed plates, respectively, a collar longitudinally adjustable on said shaft and an additional movable plate carried by said collar. 125

6. In a condenser, a plurality of fixed plates, a shaft, a plurality of movable plates 130

- carried by said shaft and adapted to pass between said fixed plates, respectively, upon rotation of said shaft, means adapted to surround a portion of said shaft and to be adjusted in frictional relation thereto and by means of said frictional engagement to maintain the said movable plates in any adjusted position relative to said fixed plates, and an additional movable plate carried by said shaft outside of an outermost fixed plate, and means permitting adjustment of said additional plate longitudinally of said shaft, independently of said plurality of movable plates, whereby the normal capacity of said condenser may be regulated, said additional plate adapted to be rotated by said shaft simultaneously with the other of said movable plates.
7. In a condenser, a base, a plurality of fixed plates carried by said base, a shaft, a plurality of movable plates mounted as a unit on said shaft and arranged to pass between said fixed plates, respectively, upon rotation of said shaft, means adapted to surround a portion of said shaft and to be adjusted in frictional relation thereto and by means of said frictional engagement to maintain the said movable plates in any adjusted position relative to said fixed plates, an additional movable plate on said shaft outside of an outermost fixed plate and means permitting adjustment of said additional plate longitudinally of said shaft, independently of said plurality of movable plates, whereby the normal capacity of said condenser may be regulated, said additional plate adapted to be rotated by said shaft simultaneously with the other of said movable plates.
8. In a device of the character described, a plurality of condensers, each including a plurality of fixed plates and a plurality of movable plates arranged to pass between said fixed plates, respectively, a support for said movable plates, a common actuating means for said support, and an additional movable plate secured to means slidably carried on said movable plate support associated with each plurality of fixed plates and adjustable relatively thereto independently of the corresponding plurality of movable plates, whereby the normal capacities of the condensers may be regulated.
9. In a device of the character described, a plurality of condensers, each including a plurality of fixed plates and a plurality of movable plates, a shaft upon which said movable plates are mounted, said movable plates being arranged to pass between the said fixed plates, respectively, upon rotation of said shaft, an additional movable plate mounted on member slidable on said shaft at one side of an outermost fixed plate of each plurality of fixed plates and means permitting adjustment of said additional plates longitudinally of said shaft, independently of the corresponding plurality of movable plates, whereby the normal capacities of said condensers may be regulated.
10. A device of the character described including a mounting frame, a pair of insulating strips secured to said mounting frame, a plurality of stationary plates, spacing members for supporting said stationary plates in spaced relation, means integral with certain of said spacing members for securing said stationary plates to said insulating strips, a rotatable shaft supported by said mounting frame, a plurality of movable plates supported on said shaft and associated with said stationary plates, means for rotatably moving said movable plates simultaneously in relation to said stationary plates, and independent means slidable on said shaft for supporting and for varying the space between certain stationary and movable plates, said certain plates adapted to be rotated simultaneously with the other of said movable plates.
11. In a condenser, a U-shaped frame, stationary plates, spacing members for supporting and spacing said plates, means integrally formed with certain of said spacing members attached to insulating strips secured to the intermediate portion of said frame, a rotary shaft extending through the free ends of said frame, a plurality of movable plates carried by said shaft and adapted to be positioned between said stationary plates, respectively, an additional movable plate mounted on a collar adjustably supported on said shaft and means permitting adjustment of said additional plate supported on said collar longitudinally of said shaft and independently of said plurality of movable plates.

In testimony whereof I have signed this specification.
